UNITED STATES PATENT OFFICE.

ALFRED BLOUIN, OF HOLYOKE, MASSACHUSETTS, ASSIGNOR TO DRAPER CORPORATION,
OF HOPEDALE, MASSACHUSETTS, A CORPORATION OF MAINE.

FEELER-MOTION FOR LOOMS.

1,311,747.

Specification of Letters Patent. Patented July 29, 1919.

Application filed October 23, 1918. Serial No. 259,372.

To all whom it may concern:

Be it known that I, ALFRED BLOUIN, a subject of the King of Great Britain, and a resident of Holyoke, in the county of 5 Hampden and State of Massachusetts, have invented an Improvement in Feeler-Motions for Looms, of which the following description, in connection with the accompanying drawings, is a specification, like characters 10 on the drawings representing like parts.

The invention to be hereinafter described relates to feeler motions for looms whereby when the filling becomes substantially exhausted in the shuttle a fresh supply is 15 furnished without stopping the loom.

The object of the present invention is to provide a feeler motion of the above generally stated character which shall be simple in construction, effective and reliable in 20 operation, and wherein the parts may be readily assembled and repairs made when the parts of the feeler motion become worn. The feeler motion of the present invention is preferably embodied in and designed as 25 an improvement on that type of feeler shown and described in the patent to Roper No. 821,123 and dated May 22, 1906, wherein the feeler comprises two feeler members, one a penetrating and the other an impinging member.

In those feeler motions wherein a controller is employed for initiating filling replenishment when the filling in the shuttle has become substantially exhausted, it has 35 heretofore been usual to provide the end of the controller with a dove-tailed notch or otherwise form the end of the controller to engage an arm when and during the frontward movement of the controller the filling

40 has become substantially exhausted. In these constructions when the end of the controller becomes worn under constant use, it is difficult to prolong the life of the feeler owing to the fact that the end engaging 45 portion of the controller is seldom susceptible of repair. One of the objects of the present invention is to provide a controller and coöperating parts which will permit such parts to be readily repaired and placed 50 in good working condition even after they have become worn. Other features of the invention and novel characteristics thereof will be hereinafter pointed out in addition to the above and the novel constructions definitely set forth in the claims.

In the drawings:

Figure 1 is a perspective view showing one end portion of a loom and associated parts with the present invention associated therewith;

Fig. 2 is an enlarged central longitudinal section of the feeler showing the normal position of parts when a working supply of filling is present in the shuttle;

Fig. 3 is a similar view to that of Fig. 2 showing the position the parts assume when, on a detecting beat, the feeler detects substantial exhaustion of filling; and

Fig. 4 is a view similar to that of Fig. 3 showing the controller and the position it assumes under the frontward pressure of the filling carrier in the shuttle when filling is substantially exhausted and the lay moves to front position.

Referring more particularly to Fig. 1 of 75 the drawings, the loom frame 1 has connected thereto the usual bracket 2 slotted at 3 for the movement of the shipper 4 and extended for the support of the feeler stand. It may be secured to the bracket 2 in any 80 approved manner as will more fully appear.

Secured to the loom frame 1 are the brackets 5 provided with bearings 6 for the usual transverse or rock-shaft 7 which, as usual in feeler looms, is under the influence of a 85 spring for holding the rock-shaft 7 in normal position and yet permitting it to be rocked upon call for filling replenishment, as will be well understood by those skilled in the art.

Secured to and rising from the transverse or rock-shaft 7 is the finger 8 having pivoted thereto at 9 the arm 10 which, for purposes of identification, may hereinafter be termed the actuator. The arm 10 extends rearwardly as indicated in Fig. 1 and upon call for filling replenishment is adapted to be engaged by an operating member 11 which may be connected to any suitable moving part of the loom as, for instance, 100 the cam follower.

The feeler stand 12 is secured to the supporting bracket 2 or other convenient sustaining means by the bolts or screws 13 which pass through a slot 14 in the feeler stand and thereby permit suitable adjustment. The feeler stand 12 has mounted therein for reciprocating movement a feeler slide 15 the front portion of which extends into the feeler stand as indicated in Fig. 1 110

and is normally under the influence of a spring 16 tending to maintain the feeler slide 15 in its rearward position to permit such slide to be moved frontwardly.

5 The feeler slide 15 carries an impinging and a penetrating feeler member and in the present instance of the invention the impinging member consists of the rear end portion 17 projecting rearwardly from the 10 feeler slide and provided with a passage-way through which extends the penetrating member of the feeler. In the present instance the penetrating member of the feeler consists of a finger 18, the rear end portion 15 19 of which is preferably sharpened or made wedge-shape in order that it may sink into the filling when, on a detecting beat, a working supply is present in the shuttle. Frontwardly of the impinging portion 17 of the 20 feeler slide the penetrating feeler member has an upwardly extending portion 20 adapted to engage an adjusting device 21 carried by the controller 22. In the present instance the controller 22 is pivotally 25 mounted at 23 on the feeler slide 15 and has upwardly projecting portions 24, 25, through which the adjusting device 21 passes and wherein it is adjustably mounted. If desired, the adjusting device 21 may be 30 locked in adjusted position by means of a lock nut 26.

The controller 22 extends frontwardly from its pivotal support 23, and its end portion 27 is preferably supported by a yielding device to normally maintain the end portion 35 27 in position as indicated in Fig. 2.

In feeler motions as heretofore constructed, it has been the usual practice to finish such end portion and provide it with a recess or fan tail which was designed to engage a similarly formed portion of a lever or similar part and move it toward the front of the loom when, on a detecting beat, the filling was substantially exhausted. In 40 such forms of controllers where the end portions have been especially prepared and formed, it was practically impossible to draw the metal and provide the necessary dove-tail construction after such part had 45 become worn and thereby rendered the feeler action unreliable. In the present invention, however, the end portion of the controller 22, as will be obvious from the illustrations of Figs. 2, 3 and 4, is not of special dove-tail 50 formation but is formed plain or blunt so that when the end of the controller becomes worn and no longer acts with certainty by reason thereof, it is only necessary to draw the metal slightly to thereby return the controller to its full operative condition. The 55 life of the feeler is thereby prolonged and the feeler susceptible of ready repair.

A rock-shaft 28 extends between the feeler and actuator and has a lug or projection 60 29 extending therefrom and adapted at

times, as will more fully appear, to be engaged by the blunt ended controller to cause rocking movement of the rock-shaft and thereby place the actuator in operative position with its operating member. In the 70 present instance of the invention the feeler stand is provided with a bearing portion 30 above the feeler slide in which the rock shaft 28 is mounted for rocking movement and an opening 31 is formed in the feeler stand through which extends the projection or lug 29 formed on or secured to the rock-shaft 28.

The rock-shaft 28 is preferably also sustained by bearings 32 rising from a bracket 80 33 secured to the loom frame in proximity to the actuator 10. The end of the rock-shaft adjacent the actuator 10 is provided with a lug 34 preferably formed as a cam adapted to engage a recess or opening 35 in 85 the actuator 10, the construction being such that the actuator 10 will normally be in lowered or inoperative position with respect to its operating member 11 and will, perforce, through the cam 34 cause the shaft 90 28 to rock contraclockwise viewing Figs. 2, 3 and 4. In order to maintain the rock-shaft in normal position for engagement of lug 29 by the controller when the filling has 95 become substantially exhausted on a detecting beat, the feeler stand is provided with a stop shoulder 36 against which the lug or projection 29 normally rests, as indicated in Figs. 1, 2, under the weight of the actuator 10. Endwise movement of the shaft 28 in its 100 bearings is prevented by means of collars 37 secured thereto at opposite sides of the bearings 32.

As indicated in Fig. 1 the front wall of the shuttle box 38, as well as the front wall 105 of the shuttle 39, are provided with suitable openings as usual in feeler loom constructions, through which the feeler members may pass as the lay beats up in order to detect the condition of the filling in the shuttle. 110

When the parts are in normal operating position and the loom is running with a working supply of filling, the controller 22 is supported by the yielding post 40 about the lower end of which is placed a spring 115 41 tending to raise the post 40 into the position indicated in Fig. 2 but yieldable to permit the controller 22 to be turned about its pivotal mount 23 on the feeler slide into the position indicated in Figs. 3 and 4. 120

From the construction described it will be apparent that when the loom is running and a working supply of filling is present in the shuttle, as indicated in Figs. 1 and 2, the penetrating member 18 will sink into the 125 filling 42 on the filling carrier 43 as the lay moves to its front position and the feeler slide will be moved frontwardly. Under such conditions the blunt end portion 27 of the controller 22 will move frontwardly in 130

a path of non-intersection with the lug or projection 29 of the rock-shaft 18 and the loom will continue in operation without change of filling. When, however, the filling becomes substantially exhausted as indicated in Figs. 3 and 4, the penetrating feeler member 18 will first contact with the more dense surface of the bobbin and be moved forwardly as indicated in Fig. 3, relative to the impinging feeler 17, thereby turning the controller 22 with its end in position to intersect the projection 29 of the shaft 28, and upon further forward movement of the lay the feeler slide and, perforce, the controller will be moved forwardly, thereby causing the blunt end portion 27 of the controller to impinge upon the lug or projection 29 and turn it from the position indicated in Fig. 3 to that indicated in Fig. 4, thereby rocking the shaft 28 and lifting the actuator to place its end in operative position to its operating member 11. As the feeler slide 15 continues its forward movement, its end portion will ride over the lug or projection 29 after the latter has been turned downward into the position indicated in Fig. 4 and the forward pressure of the filling carrier or bobbin upon the penetrating member will maintain the controller in the position indicated in Fig. 4 and thereby hold the lug or projection 29 in its down-turned position and the actuator in its raised position for engagement by its operating member.

Should the end portion 27 of the controller become worn under the constant use to which it is subjected, or should the lug 29 projecting from the rock-shaft 28 become unduly worn, the metal of such parts or either of them may be drawn or readily reformed.

It may sometimes be desirable to adjust the length of the shaft 28 or the relative angular position of the cam 34 and the lug 29 and in the present instance of the invention this is accomplished by means of a turn-buckle 44 and when the parts have been suitably adjusted they may be locked in such position by means of screws or other fastenings 45.

50 Claims:

1. In a feeler motion for looms, the combination of a feeler member, an actuator and operating member, a rock shaft extending between the actuator and feeler members and having a projection, a controller having an end portion normally maintained for movement in a path above the projection from the rock shaft when a working supply of filling is present in the shuttle and movable into position to intercept the projection and turn the rock shaft and then ride over and bear upon the depressed projection when the filling is substantially exhausted on a detecting beat, and connections between the rock shaft and actuator.

2. In a feeler motion for looms, the combination of an actuator and operating member, a feeler slide and feeler, a rock shaft extending between the feeler slide and actuator and having a lug or projection, a controller mounted to move with the slide and having an end portion maintained for movement in a path of non-intersection with said projection when a working supply of filling is present in the shuttle on a detecting beat and movable into position to intercept said projection and turn the rock shaft and then ride over and hold the projection depressed when the filling in the shuttle is substantially exhausted on a detecting beat, and a cam connection between the rock shaft and actuator. 70

3. In a feeler motion for looms, the combination of a feeler stand, a feeler slide, a penetrating and an impinging feeler member carried by the slide, an actuator and operating member, a rock shaft supported for rocking movement in the feeler stand and extending between the feeler stand and actuator, a lug or projection extended from the rock shaft adjacent the feeler stand, a controller mounted to move with the feeler slide and having an end portion normally maintained for movement above the lug or projection on the rock shaft when a working supply of filling is present in the shuttle on a detecting beat and movable into a position to engage and turn the lug or projection when the penetrating feeler member indicates substantial exhaustion of filling and then ride over and hold the lug or projection depressed and the shaft turned as the lay moves to its front position, and connections between the rock shaft and actuator. 85

4. A feeler motion for looms, comprising, in combination, a feeler stand, an actuator, a rock shaft extending directly between the feeler stand and actuator, a lug projecting from the rock shaft through the feeler stand, a stop against which the lug normally bears, 100 a feeler slide mounted for reciprocating movement in the feeler stand, a controller movable with the feeler slide and having an end normally maintained for movement in a path of non-intersection with said lug as the slide moves forwardly when a working supply of filling is present in the shuttle on a detecting beat, a feeler member mounted on the slide and acting to move the end of the controller into position to intercept the lug on the rock shaft when the filling is substantially exhausted on a detecting beat and then ride over and bear upon the lug in turned position by the pressure of the filling carrier upon the feeler member. 110

5. A feeler motion for looms comprising, in combination, a feeler stand, a feeler slide mounted for reciprocating movement in the feeler stand, an actuator, a rock shaft supported for rocking movement in the feeler stand, 120

- 1 stand above the feeler slide and having a lug or projection projecting through the feeler stand, a controller mounted on the feeler slide and having an end portion normally 5 maintained for movement in a path above the top of said lug or projection when a working supply of filling is present in the shuttle on a detecting beat, and a feeler member acting under the forward pressure of the filling carrier to move the end of the controller into position to intercept said lug or projection and turn the rock shaft when the filling is substantially exhausted on a detecting beat and then ride over and bear 10 upon the lug or projection.
- 15 6. In a feeler motion for looms, the combination of a feeler slide, a feeler stand having an opening and a stop shoulder, a rock shaft mounted for rocking movement in the 20 feeler stand above the feeler slide and having a lug projecting through the opening in the feeler stand, an actuator connected to the rock shaft and acting to normally maintain the lug against the stop shoulder, a controller movable with the feeler slide and having a blunt end maintained for movement in a path above the said lug when a working supply of filling is present in the 25 shuttle on a detecting beat, and a feeler member acting under the forward pressure of the filling carrier to depress the blunt end of the controller and cause it to 30 turn and then ride over the depressed lug

when the filling is substantially exhausted on a detecting beat. 35

7. In a feeler motion for looms, the combination of a feeler member to feel for the filling in the shuttle, an actuator and an operating member, a transmitter between the feeler member and actuator having an extended portion, a controller movable by the feeler member and having a blunt actuating end which is normally maintained for movement in a path of non-intersection with the extended portion of the transmitter when a 40 working supply of filling is present in the shuttle, and movable into position to intercept and strike the said extended portion and turn it when the filling is substantially exhausted on a detecting beat and the controller is moved forwardly and then to ride over and bear upon the extended portion as the controller moves forwardly, the blunt striking unsocketed end of the controller adapted to be extended or drawn 45 lengthwise of the controller to compensate for wear, and connections between the transmitter and actuator to position the actuator operatively relative to the operating member when the blunt end of the controller 50 strikes and moves the extension of the transmitter. 55

In testimony whereof, I have signed my name to this specification.

ALFRED BLOUIN.
